DANIEL DUNCAN AND E. R. RIDGLEY, OF OLNEY, ILLINOIS.

Letters Patent No. 65,889, dated June 18, 1867.

COMBINED SOWER, PLANTER, AND CULTIVATOR.

The Schedule referred to in these Letters Patent and making part of the same.

TO ALL WHOM IT MAY CONCERN:

Be it known that we, D. DUNCAN and E. R. RIDGLEY, of Olney, in the county of Richland, and State of Illinois, have invented a new and improved Combined Planter, Cultivator, and Roller; and we do hereby declare the following to be a full, clear, and exact description of the same, reference being had to the accompanying drawings, forming part of this specification, and in which—

Figure 1 represents a view of my machine from a point vertically above it.

Figure 2 is a side elevation of the same.

Figure 3 is a vertical sectional elevation through the centre of the seed-box, showing the construction and operation of that box.

Similar letters of reference indicate corresponding parts in the several figures.

The object of my invention is to construct a machine, which shall be capable of being used as a planter, a cultivator, a roller, or all together, and which, while it is convenient to manage in the field, shall be strong and durable.

A A A A represent the frame, B the draw-beam attached to the frame, C the driver's seat, D the seed-box, and E E' the rollers turning upon the axles e e e e, which work in boxes attached to the under side of the frame A A. On one end of the roller E is fastened the ring F, shown in fig. 2, which is furnished with short projecting arms f f f f, the purpose of which will be hereinafter explained. G is a square iron bar or shaft turning in boxes or sockets g g g. Sliding upon this bar is an armature, H, which projects far enough inward to come in contact with the arms f f f f upon the ring F as the roller revolves. The armature H is slid backward and forward upon the shaft G, by means of the lever I, pivoted at i, and terminating in a treadle near the driver. K is a second armature attached to the shaft G, not movable upon the shaft like the one above described, but firmly fixed in its place, and connected at its extremity with the sliding bottom of the seed-box by the link k. The construction of the seed-box D is clearly shown in fig. 3. Its bottom is perforated at l l l, and it has a secondary sliding bottom also similarly perforated, which, at one end, is connected with the armature K, and at the other end is attached to the spring L in fig. 3. m m represent the perforations through the secondary sliding bottom.

M M', fig. 1, represent two shafts turning in sockets attached to the frame and draw-beam, and supporting the drill-teeth of the cultivator. The latter are arranged four upon each shaft, and have posterior conducting tubes, as shown at N, fig. 2. The shafts M M', operating entirely independent of each other, may be turned so as to raise their respective drill-teeth from the ground by simply pressing the foot against the treadles n n'. O O are pawls to keep the treadles n n' in place. P P are pins to confine and steady the seed-box.

The operation of a machine thus constructed is as follows: The seed is placed in the seed-box, the bottom of which is closed, and the machine is put in motion. The driver pushes the treadle I with his foot until the armature H comes in contact with the arms upon the revolving ring F. As one of these arms strikes the armature H the latter is forced downward, communicating its motion to the shaft G, which in its turn operates the armature K, forcing it outward, and by means of the link k drawing the secondary bottom of the seed-box along until the holes m m come in a vertical line with the holes l l, when the seed will drop from the seed-box through the conducting tubes N to the ground. As the secondary bottom of the seed-box is thus moved it bends the spring L, and when, by the further revolution of the ring F, the arm which has been bearing upon the armature H passes the armature and leaves the latter free, the force of the spring L returns the secondary bottom of the seed-box, with its connected apparatus, the link k, armature K, shaft G, and armature H, to their original places, where they are ready to repeat the same movements above described whenever the next approaching arm of the ring F shall come in contact with the armature H, thus opening and closing the holes in the bottom of the seed-box as many times at every revolution of the rollers as there are projecting arms upon the ring F.

Having thus explained the construction and operation of our machine, what we claim as new, and desire to secure by Letters Patent, is—

1. The shaft G, having the fixed armature H working the secondary bottom of the seed-box D, and having the sliding armature K regulated by means of the lever and treadle I, substantially as and for the purpose described.

2. The ring F on the end of the roller E, provided with projecting arms *fffff*, substantially as described.
3. The division of the shaft M M', to which are attached the drill-teeth, into two equal parts, M and M', independent of each other, and regulated by means of their respective treadles *n.n'*, substantially as and for the purpose described.

4. The combination and arrangement of the spring L, the secondary bottom of the seed-box, the shaft G, with its two armatures K and H, and the roller E having the ring F with its arms *fffff* attached, substantially as and for the purpose specified.

5. The combination and arrangement of the drill-teeth attached to the shafts M M', the seed-box D, and the rollers E E', substantially as and for the purpose specified.

The above specification of our invention signed by us this 5th day of September, 1866.

DANIEL DUNCAN,
E. R. RIDGLEY.
